ABSTRACT OF THE DISCLOSURE

A regulator device for use with induction apparatus such as transformers, induction coils and the like for adding and subtracting in-circuit turns comprises a core surrounding which is a helical flexible, insulated regulator winding. One end of this winding is fixed, the other end is arranged for movement along a circular path about the core axis, and a cylindrical mobile guide member is located on the core intermediate upper and lower sections of the winding, the turns of the upper and lower winding sections being wound in opposite directions and being separated by a direction reversing portion which passes along a U-shaped transition groove in the guide member. When the movable end of the winding is moved along its circular path, it entrains all of the winding section between it and the guide member, effects movement of the direction reversing portion of the winding along the groove of the guide member and thus adds turns to one of the winding sections while simultaneously subtracting turns from the other section, the guide member being displaced longitudinally along the core in one direction or the other depending upon the sense of rotation of the movable end of the winding. All turns of the regulator winding are thus always traversed by the current and the desired regulation is effected by arranging for an increase in the number of turns having one direction of winding and a simultaneous decrease in the number of turns having the opposite direction of winding.

The present invention relates to a regulator device for use on electrical induction apparatus such as transformers and the like which functions to change the number of in-circuit turns of an electrical coil by adding or subtracting coil turns.

In the case of an electrical transformer, for example, in order to regulate, i.e. vary the secondary output voltage, it is necessary to vary the number of in-circuit turns of either the primary or secondary winding, thus changing the turns ratio of the transformer by the desired amount. When the nature of the operation requires that the output voltage of the transformer be varied without an interruption in service, various expedients are available, among which are:

(a) Use of a load assumption commutator, often located on the primary side of the transformer.

(b) Use of a carbon traveller which passes from one turn to the other along a generatrix of a cylindrical winding.

(c) Use of a transformer with a rotary core in which a traveller, secured to the core, slides inside the turn of the secondary winding and thus permits an absolutely continuous variation of the output voltage.

The primary object of the present invention is to provide an entirely different arrangement for effecting the desired result of adding or subtracting coil turns which functions in such manner that no portion of the winding to be regulated is ever "open-ended" during the regulation,

2

i.e. not traversed by the current which passes through the winding.

In accordance with the invention, a cylindrical regulating coil with a helical winding is supported for rotation about its axis between two concentric, mobile cylinders, the cylindrical core of the induction device being located interiorly of the innermost mobile cylinder. One end of the helical winding is fixed while the other end is subjected to rotation in a circle about the core axis and the winding is composed of two axial sections effectively separated by a cylindrical mobile guide piece also mounted between the concentric mobile cylinders. Those turns of the winding section located between the fixed end thereof and the guide piece are wound in one direction about the core, and those turns of the winding section located between the rotatable end thereof and the guide piece are wound in the opposite direction about the core. The desired transition in the respective winding directions of the two sections which takes place at the guide piece is effected by passing the intermediate portion of the flexible wire which forms the winding through a generally U-shaped groove in the guide piece. Thus, as the movable end of the winding is rotated in a circular path concentric with the core axis, the intermediate portion of the winding will move in one direction or the other through the groove in the guide piece and simultaneously cause the latter to travel longitudinally of the core in one direction or the other as the number of turns of one section of the winding is increased, while the number of turns on the other winding section is simultaneously decreased. The direction of longitudinal movement of the guide piece will, of course, be dependent upon the direction of rotation of the movable end of the winding in its circular path about the core axis.

The foregoing as well as other objects and advantages inherent in the invention will become more apparent from the following detailed description of two practical embodiments thereof as applied to a transformer and from the accompanying drawings wherein:

FIG. 1 is a view in central vertical section with certain parts shown in elevation of the coil supporting part of a transformer core;

FIG. 2 is a plan view of the structure shown in FIG. 1; FIG. 3 is a generally elevational view of the regulator winding showing its relation to the mobile guide piece which serves to effect the desired change in turns of each section of the winding such that the number of turns of one section which are wound in one direction will be progressively increased while the number of turns of the other section which are wound in the opposite direction will be progressively decreased;

FIG. 4 is a transverse view at the rotatable end of the regulator winding showing the manner in which the electrical connection to this end of the winding is made; and

FIG. 5 is a view similar to FIG. 3 and illustrating a modified embodiment wherein two regulator windings incorporating the inventive concept are arranged in superposed relation on the same transformer core.

With reference now to the drawings, and in particular to the embodiment illustrated in FIGS. 1-4, the transformer is comprised of a magnetic circuit which includes a plurality of cylindrical cores 1 on which the transformer coils are placed, and end yokes 2 which serve to support and magnetically interconnect the cores 1 to establish the necessary closed flux path through the structure. The cylindrical cores 1 and end yokes 2 are laminated, as is conventional. Thus, the laminations of the cores 1 may be contoured as involutes of a circle, or the laminations may be arranged radially from the axis or stacked in any other classic manner. Similarly, the lami-

nations of the end yokes 2 may be wound from strips of magnetic sheet material or arranged in other classic manners. The number of cores 1 will depend upon whether the transformer is designed for single-phase or three-phase use. If single-phase, there will be two such cores interconnected by the end yokes, and for a three-phase arrangement, three such cores will be used and arranged, for example, at the apices of a triangle.

The end yokes 2 are secured to the opposite ends of each core 1 by means of a through bolt 3 which passes through the center of the core and yokes 2, the bolt having a head 5 at one end and a clamping mechanism 4 at the opposite end. Insulators 6 at the opposite end face of each core serve to prevent the laminations of the core and end yokes from coming into direct contact with each other.

The coil arrangement on each core 1 comprises a cylindrical primary winding 7 to which is usually applied a high voltage, a main cylindrical second winding 8 located radially inward from primary winding 7 and electrically insulated therefrom by means of a cylindrical sheath 9 of insulating material, and a generally helical regulator winding 11 which is connected in series with secondary winding 8. This regulator winding 11 located radially inward from secondary winding 8 is made from a flexible conductor material covered by a braided type of insulation, or the like.

One end of secondary winding 8 is passed through terminal bushing 10 and the opposite end of this winding is connected via a conductor 12a to the lower end 12 of the regulator winding 11, this lower end being fixed in position. The opposite end 13 of the regulator winding is mobile, as distinguished from its opposite, fixed end 12, and is arranged to be moved in a circular path concentric with the axis of the core 1 in a clockwise, or counter-clockwise direction by means including a rotatable crown wheel 14 which surrounds one end of core 1 and which preferably is made from insulating material.

A stationary crown wheel 15, also made from insulating material surrounds core 1 at its opposite end, and these two crown wheels are provided with cylindrical portions 14', 15' which serve to center, in radially spaced relation two mobile insulating sleeves 16, 17 and between which lies the regulator winding 11.

As can be seen from FIG. 3, the helical regulator winding 11 although continuous throughout its length, is functionally divided into two operating sections 11A and 11B, the lower section 11A being wound in one direction as related to the axis of the core 1, and the upper section 11B being wound in the opposite direction. Intermediate between these two sections is located a cylindrical, mobile guide member 18 which is provided with a U-shaped groove 18' through which the flexible conductor which forms regulator winding 11 is passed and guided in effecting the desired reversal in the respective winding directions of the upper and lower sections 11A and 11B. Guide member 18 also lies between insulating sleeves 16, 17 and functions somewhat as a pulley, guiding the wire into and out of the winding direction-changing groove 18' and shifting axially so that the number of turns of winding sections 11A and 11B of the regulating winding progressively increase and decrease, respectively, or vice versa, as the drive crown 14 is rotated. Rotation of drive crown 14 may be effected in any suitable manner such as by means of a ring gear 23 secured to it, the ring gear being meshed with a reversible drive pinion, not illustrated. Ring gear 23 is preferably made from electrical insulating material. If made from a metal which is electrical conductive, it is preferable to interrupt the same circumferentially by means of insulating inserts to prevent formation of short-circuited turns around core 1.

The details of the manner in which the upper, mobile end 13 of regulator winding 11 is arranged for rotation in a circular path about the core axis, and the manner in which the necessary electrical connection to this coil end

is made, are shown in FIG. 4. Here it will be seen that the drive crown wheel 14 includes a circumferentially extending recess 14'' within which are located two spring loaded electrically conductive travellers 24 connected to the end 13 of winding 11 which establish, as they rotate with crown wheel 14, a sliding contact with arcuate, electrically conductive shoes 25 arranged in a circle in essentially end-to-end relation, but electrically insulated from each other to avoid creation of a short-circuited turn. The arcuate shoes 25 are secured to the outer ends of a circular array of electrically conductive strips 26 having the configuration of involutes positioned at the top 20 of core 1 where some of the involute-shaped magnetic sheets are shortened. The involute-shaped conductive strips 26 which are also insulated from the magnetic sheets which form the core are secured at their inner ends, such as by welding, to the periphery of an electrically conductive, stationary sleeve 21 surrounding rod 3 in spaced relation thereto. Sleeve 21 extends upwardly beyond the upper surface of yoke 2, and a collar 22 provides the necessary electrical take-off connection from sleeve 21 to and for passage through the other terminal bushing 19. The conductive strips 26 are provided in sufficient number to prevent any sparking as the drive crown 14 is rotated.

The commutation arrangement which has been described is particularly suitable for cores formed of involute-shaped magnetic sheets. For other types of cores one can, by subdividing the cores in known manner, establish an analogous commutation arrangement for the mobile end 13 of the regulating winding 11.

Operation

The improved turn-changing regulating device in accordance with the invention operates in the following manner.

In order to effectively change the number of turns of regulating winding 11 connected in circuit with the main secondary winding 8, gear 23 is rotated in one direction or the other, dependent upon whether turns are desired to be added or subtracted, to rotate crown 14. During rotation of crown 14, the mobile end 13 of the regulating winding 11 also rotates and entrains all of that part 11B located between the guide member 18 and the mobile end 13. The guide member 18, also entrained due to the friction which exists between it and the braided insulating covering for winding 11, moves in the manner of a pulley, in one direction or the other axially along the core 1, dependent upon the direction of rotation of winding end 13, as the wire passes through the U-shaped reversing groove 18', thus passing the turns of winding 11 one-by-one from section 11A to section 11B, or vice versa.

If the number of arcuate collecting shoes 25 is designated by p , and the flux involved varies by $1/p$ for each increment $1/p$ of rotation of drive crown 14 in a given direction, the number of additional turns diminishes, for example, by $1/2p$ of a turn and, when subtracting, increases by $1/2p$ of a turn, so that the total voltage change actually varies by $1/p$ multiplied by the voltage per turn.

The improved regulating device according to the invention, as described hereinabove by a way of example, for application to the regulation of the secondary voltage of a transformer can also, without departing from the scope of the inventive concept, be used with induction coils or other types of induction apparatus, with the use of suitable devices for its functioning within the spirit of what has been described.

Finally, it is possible, with a view towards particular and complex regulating functions, to make use of a plurality of regulating devices as described, these being coupled together in a desired manner and connected electrically to the apparatus to be regulated. An arrangement of this type, making use of two such regulating devices, is illustrated in FIG. 5, as an example. Here it will be seen that the two regulating windings 111 and 211 are

associated with guide members 18a, 18b, respectively, and drive crowns 14a, 14b respectively arranged on a common core and located at opposite ends thereof. The fixed ends 111' and 211' of the windings are interconnected at the common, stationary crown wheel 15' located at an intermediate position of the core and lead to an interconnection between the adjoining ends of the two main secondary windings 8' and 8''.

I claim:

1. In a regulator device for changing the number of in-circuit turns of an induction apparatus, the combination comprising a core, a helical, flexible regulator winding located on said core, means securing one end of said winding against rotation, means for moving the other end of said winding in a circular path about the core axis, and a cylindrical mobile guide member located on said core intermediate upper and lower sections of said helical winding, the turns of said upper and lower sections being wound in opposite directions respectively and being separated by a direction reversing portion which passes along a direction reversing groove in said guide member, whereby movement of said one end of said winding along its circular path serves to effect movement of said direction reversing portion thereof along said groove in said guide member thus adding turns to one of said winding sections and simultaneously subtracting turns from the other section and which is accompanied by a displacement of said guide member longitudinal of the core axis.

2. A regulator device as defined in claim 1 wherein said means for moving one end of said regulator winding in a circular path about the core axis is constituted by a drive crown mounted on said core adjacent said winding end and which further includes a fixed crown located on said core adjacent the opposite end of said winding and secured thereto, and mobile concentric insulating sleeves between which said crown wheels, regulator winding and guide member are located and centered.

3. A regulator device as defined in claim 1 wherein said core is provided with an axially extending through-bore and through which passes a rod for clamping op-

5

posite ends of said core to yoke members, wherein said means for moving one end of said regulator winding in a circular path about the core axis is constituted by a drive crown, and which further includes a pair of spring loaded electrically conductive travellers located in a recess in said drive crown, said movable end of said winding being secured to said travellers, a circular arrangement of a plurality of arcuate stationary collecting shoes concentric with the core axis and disposed in essentially end to-end relation but electrically insulated from each other, an electrically conductive sleeve surrounding rod, conductive strips having involute configuration interconnecting said arcuate collecting shoes with said conductive sleeve, and an electrical connection from said conductive sleeve to terminal means.

4. A regulator device as defined in claim 3 and which further includes a fixed crown located at the opposite end of said regulator winding and to which winding end said fixed crown is secured, and mobile concentric insulating sleeves between which said crown wheels, regulator winding and guide member are located and centered.

5. A regulator device and which includes a plurality of helical flexible regulator windings each as defined in claim 1 and which are arranged on a common core and electrically interconnected.

6. A regulator device as defined in claim 1 for use with a transformer wherein the primary and secondary transformer windings are located on said core, and said regulator winding is connected in series with said secondary winding of said transformer.
